DESIGN FOR A DRESS

Phyllis Byrnes, New York, N. Y.

Application February 12, 1940, Serial No. 90,199

Term of patent 3½ years

To all whom it may concern:

Be it known that I, Phyllis Byrnes, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is the back view of my dress on a reduced scale, and

Fig. 3 is a fragmentary side view of the upper portion of the dress showing the sleeve member.

I claim:

The ornamental design for a dress, substantially as shown.

PHYLLIS BYRNES.
